ATTORNEY.

UNITED STATES PATENT OFFICE.

ARTHUR ALBERT DOWNING, OF TORONTO, ONTARIO, CANADA.

FLOOR-WAXING DEVICE.

1,215,505.

Specification of Letters Patent.

Patented Feb. 13, 1917.

Application filed July 6, 1915. Serial No. 38,390.

To all whom it may concern:

Be it known that I, ARTHUR ALBERT DOWNING, a subject of the King of Great Britain, and resident of 144 Victoria street,

5 in the city of Toronto, county of York, Province of Ontario, in the Dominion of Canada, have invented certain new and useful Improvements in Floor-Waxing Devices, of which the following is a specification.

10 The invention relates to improvements in floor waxing devices as described in the present specification and shown in the accompanying drawings that form part of the same.

15 The invention consists essentially of the novel construction and arrangement of parts whereby the wax is automatically deposited on the floor in advance of a weighted block and is distributed over the floor surface by 20 means of a pad on the underside of said block.

The objects of the invention are to economize in the consumption of wax, to facilitate the waxing of floors and generally to provide a simple, cheap, durable and efficient 25 floor waxing device.

In the drawings, Figure 1 is a side view of the device.

Fig. 2 is a view of the bottom of the device.

30 Fig. 3 is a plan view of the device.

Fig. 4 is a detail of the bar used to lock the distributing pad in position.

Like numerals of reference indicate corresponding parts in each figure.

35 Referring to the drawings, 1 is a metal block rigidly secured to the wooden base 2 and having the notches 3 extending inwardly from the ends 4 and 5 adjacent to the lower sides thereof.

40 6 is a pad of felt or other suitable material extending over the bottom of the base 2 and having its ends extending into the notches 3 and being detachably secured therein by means of the locking bars 7 and 45 set screws 8.

9 is a metal cylinder secured to the end 4 of the block 1 and having secured to the under side thereof the wooden base 10, said cylinder being open at its lower end and 50 forming a receptacle for the wax.

11 is a strip of hard wood, or other material, which will not scratch the floor surface, secured to the under side of the base 10 and having its ends 12 projecting inwardly toward the pad 6 to guide the wax under the said pad.

13 is a cover corresponding in size to the inner circumference of the cylinder 9 and adapted to close said cylinder from the upper end.

14 is a metal arm extending upwardly from the block 1 and having the end 15 projecting outwardly to a point directly over the center of the cylinder 9 and having on the outer end thereof the threaded eye 16 adapted to accommodate the thumbscrew 17.

18 are metal straps secured to the cover 13 and having their intermediate portions extending upwardly in arch shape and being secured together by the threaded eye 19, said eye being adapted to receive the lower end of the thumbscrew 17 so that when the said thumbscrew is actuated the straps 18 will be forced downwardly causing the cover 13 to recede into the cylinder as the wax is forced out of the lower end thereof.

20 is a handle secured in any suitable manner to the block 1 to facilitate the operation of the device.

In the use of the invention the cylinder 9 is filled with wax and the cover 13 screwed down tightly. The device is then pushed over the surface of the floor by means of the handle 20 and as the wax comes into contact with the floor the friction causes the wax to melt and to be deposited on the floor where it is guided under the pad 6 which distributes it evenly over the surface.

What I claim is:

1. In a floor waxer, a base, a metal block mounted on said base and supporting at one of its ends a hollow wax receptacle, a base secured on the under side of said receptacle, a distributor pad on the first mentioned base, rods securing the ends of said pad in notches in the ends of said block, a guide strip on the under side of said second mentioned base guiding the wax under said pad, a cover closing the upper end of said wax receptacle, means secured to said block for exerting a downward pressure on said cover and a handle for operating the device over the floor.

2. In a floor waxer, a base, a metal block mounted on said base and supporting at one of its ends a hollow wax receptacle, a base secured to the under side of said receptacle, a distributor pad on the first mentioned base, having its ends extending into notches in the ends of said block, rods extending through said notches over said ends, set screws adjustably securing said rods to said block, a guide strip on the under side of

said second mentioned base guiding the wax under said pad, a cover closing the upper end of said receptacle, metal straps secured in arch shape on said cover, a metal arm extending outwardly from said block over said receptacle and having at its outer end a threaded eye, a set screw engaging said eye and having its lower end engaging said straps for exerting a downward pressure

on said cover and a handle for operating the device over the floor.

Signed at the city of Toronto, Ontario, this tenth day of June, 1915.

ARTHUR ALBERT DOWNING.
